US00D568745S

(12) **United States Design Patent** (10) **Patent No.:** **US D568,745 S**
Bradley et al. (45) **Date of Patent:** **** May 13, 2008**

(54) **CONTAINER**

(75) Inventors: **Christopher M. Bradley**, Orinda, CA (US); **John Jamieson**, Walnut Creek, CA (US); **Jeffrey Tilley**, La Honda, CA (US)

(73) Assignee: **Colgate-Palmolive Company**, New York, NY (US)

(**) Term: **14 Years**

(21) Appl. No.: **29/278,551**

(22) Filed: **Apr. 2, 2007**

(51) **LOC (8) Cl.** **09-01**

(52) **U.S. Cl.** **D9/500**

(58) **Field of Classification Search** **D9/500, D9/502-54, 557-558, 682, 686, 688-691; D7/509-511; 215/379-385; 220/660-662, 220/669-673, 675**

See application file for complete search history.

(74) *Attorney, Agent, or Firm*—Michael J Wallace, Jr.

(57) **CLAIM**

The ornamental design for a container, as shown and described.

DESCRIPTION

FIG. 1 is a perspective view of a container showing our new design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken line showing of the interior of the bottom of the container and the container threads is for illustrative purposes only and forms no part of the claimed design.

1 Claim, 6 Drawing Sheets
